MAGNETIC COMPASS

Erich Bandoly, Rochester, N. Y., assignor to Taylor Instrument Companies, Rochester, N. Y., a corporation of New York

Application June 8, 1934, Serial No. 729,688

3 Claims. (Cl. 33—222)

This invention relates to a magnetic compass. The purpose of the invention is to provide a magnetic compass which is reliable in operation, simple in construction and inexpensive to manufacture. The various features of the invention will appear from the detailed description and claims when taken with the drawing in which Fig. 1 is a front view of a magnetic compass according to the present invention with a portion of 5 the crystal and its support broken away; and Fig. 2 is a cross-sectional view taken substantially 10 on the line 2—2 of Fig. 1.

The magnetic compass of this invention includes a case 6, having an upstanding rim 8 within 15 which the parts of the compass are enclosed. This case which is preferably molded from a suitable light material such as a phenol condensation product, is provided with an internal annular shoulder 7 to engage frictionally the edge of a 20 metallic disc 8 having imprinted thereon compass graduations. This disc preferably makes a press fit with the side of the shoulder 7 and at its center there is mounted in any suitable manner a central post 9 terminating in a point bearing. 25 This post serves as a pivot for the magnetic needle 10 which carries at an intermediate part thereof, a jewel cap 11 including a jewel bearing 12 to receive the point bearing of the post. The free 30 ends of the needle 10 terminate in the plane of an annular graduated dial member 13 having an annular shoulder 14 adapted to make a press fit with the inner surface of the upstanding rim 8 of the case. The annular shoulder 14 of the dial 35 member is provided with an off-set lug 15 engaging the end of the upstanding rim 8 to limit the inward movement of the dial member, while the free edge 17 of the lug serves as a bezel to grip a suitable transparent crystal 16, of any trans- 40 parent material, which closes the case. This

edge 17 may be spun over the beveled edge of the crystal. Thus the dial member 13 also serves as a support for the crystal.

I claim:

1. In a device of the character described, a case 5 having an upstanding rim, a dial member frictionally mounted in said case in spaced parallel relation to the bottom thereof, an index mounted for rotation in said case and having its ends terminating substantially in the principal plane 10 of the dial member, a crystal closing said case, and a bezel integral with said dial member for holding said crystal.

2. In a device of the character described, a case 15 provided with an upstanding rim, an annular dial member having a shoulder frictionally engaging said upstanding rim, said dial member extending in a plane parallel to the bottom of said case, an index mounted in said case for rotation with respect to said dial, said index having its ends in 20 substantially the principal plane of said dial, an annular lug on said shoulder engaging the edge of said rim, a crystal closing said case, and a bezel integral with said lug for holding said crystal.

3. In a device of the character described, a case 25 provided with an upstanding rim and also provided with an annular shoulder adjacent its bottom, a disc frictionally engaging said annular shoulder, a supporting shaft projecting from the center of said disc, an index mounted on said 30 shaft, an annular dial member having its principal plane in substantially the plane of the ends of said index, said dial being shaped to form an integral shoulder frictionally engaging the inner 35 wall of said rim, then turned outwardly to form a lug integral with said shoulder engaging the edge of said rim, and a crystal closing said case, said lug being turned inwardly to form a bezel for holding said crystal.
